(57) **CLAIM**

The ornamental design for a watch, as shown and described.

DESCRIPTION

FIG. 1 is a front left perspective view of the watch according to an embodiment;

FIG. 2 is a rear left perspective view of the watch illustrated in FIG. 1;

FIG. 3 is a top view of the watch illustrated in FIG. 1;

FIG. 4 is a bottom view of the watch illustrated in FIG. 1;

FIG. 5 is a light side view of the watch illustrated in FIG. 1;

FIG. 6 is a left side view of the watch illustrated in FIG. 1;

FIG. 7 is a rear view of the watch illustrated in FIG. 1;

FIG. 8 is a front view of the watch illustrated in FIG. 1;

FIG. 9 is an alternative left perspective view of the watch illustrated in FIG. 1; and,

FIG. 10 is an alternative top view of the watch illustrated in FIG. 1.

The broken lines immediately adjacent the shaded areas represent the bounds of the claimed design while all other broken lines are directed to environment and are for illustrative purposes only; the broken lines form no part of the claimed design. The broken line showing of the watch band is included for the purpose of illustrating the environmental structure and forms no part of the claimed design.

1 Claim, 9 Drawing Sheets
